(Cl. D35—2)

FIG.1

FIG.2

FIG. 1 is a top plan view of a blade for an aerator tool or the like showing my new design, the bottom being substantially the same as that of the top shown; and

FIG. 2 is a rear elevational view thereof.

My design for a substantially triangular shaped blade for an aerator tool is characterised by the specific configurations of the rear and point.

I claim:

The ornamental design for a blade for an aerator tool or the like, as shown and described.
